PORATION OF NEW JERSEY

MACHINE AND METHOD FOR FLAP SPLITTING AND HEEL-SEAT TONGUING

Application filed July 10, 1928, Serial No. 291,569, and in Great Britain July 20, 1927.

This invention relates to methods of and machines for operating upon the soles of shoes in fitting them to receive wood heels. In the manufacture of shoes having wooden 5 Louis heels, it is usual to face the breast of the heel with a flap split from the heel-seat portion of the sole and to shape the body of the heel-seat as an elongated tongue that will fit within the cup of the wood heel. This involves the operations of splitting the heel-seat end of the sole to form the breast flap and cutting the outline of the tongue in the body of the heel-seat. In one of its aspects, the 10 present invention consists in a machine organized for performing both the flap-splitting and tongue-cutting operations upon a sole presented thereto. To this end, an important feature of the invention consists in the combination of a splitting knife and a 15 tongue-cutting knife, together with means for relatively moving the sole and splitting knife, and then relatively moving the sole and the tongue-cutting knife to effect the splitting and tongue-cutting operations.

As herein shown, the sole is presented by a movable carrier to the splitting knife in forming the flap, the knife is then removed from the sole and a tongue-cutting knife is brought into action to form a tongue in the heel-seat 20 while the sole remains in the position occupied at the conclusion of the splitting operation. By such an arrangement of parts, a compact and unitary mechanism is secured whereby the desired operations may be performed in close sequence, in an accurate manner and at a single presentation of the sole.

In forming a tongue in the heel-seat, it is desirable in some types of machines to die-shape the material, so distorting the sole that a tongue of the required shape may be formed by a single movement of a straight tongue-cutting knife. In this connection, the invention contemplates as a further feature, a carrier for a sole having a die opening formed therein which is closed during the splitting operation and which may be opened at the conclusion of the splitting operation so that a portion of the heel-seat may be forced into the opening and shaped for the action of the tongue-cutting knife. This construction is

believed to be broadly novel and is of importance in that it permits the tongue-cutting operation to be effected while the sole is retained upon its carrier in the same position in which it has been located and clamped preliminarily to the splitting operation.

The splitting knife is herein shown as supported against the thrust of the sole by a train of mechanism operative to retract the knife at the conclusion of the splitting operation. This frees the sole of the splitting knife so that another operation can be conveniently performed upon it. This feature, therefore, is not limited in its application to machines for fitting the heel-seat of soles but may be usefully embodied in splitting machines where it is desired to supplement the splitting operation by some other operation upon the sole.

The invention also includes, as a feature of general application, a sole carrier having sole clamping means of novel construction arranged to permit the sole to be located freely and accurately in position and then acting automatically when the machine is started and at a predetermined point in the travel of the carrier to engage and reliably maintain the sole in position upon the carrier.

The invention also contemplates a sole pressing member located adjacent to the splitting knife and serving to control the position of the splitting knife as the sole is moved into splitting position, so as to regulate the thickness of the flap being split. A further feature of novel construction consists in mounting the presser member for bodily movement away from the sole at the conclusion of the splitting operation so that the work may be released and freely removed from the machine.

In conforming the breast flap to the curved breast surface of a Louis heel, it is desirable to mold the flap both longitudinally and transversely into conformity to the contour of the heel breast in order to improve the smoothness of the fitting and create a tendency for the flap to hug the heel surface instead of standing off from it. To this end, the invention contemplates sole feeding or presenting means combined with molding

mechanism organized to mold a breast flap which is attached at one edge to the sole. While this mechanism is shown as one unit of a machine organized also for splitting and 5 tongue-cutting, the molding mechanism with suitable sole feeding means is capable of being utilized separately and distinct from the other instrumentalities. As herein shown, however, the molding means is located to receive the flap as it is split from the sole and 10 to act automatically in timed relation to the splitting mechanism. This arrangement is important from the standpoint of securing a compact mechanical organization and one 15 wherein the flap is positively controlled in its movement and position from the point at which it is formed until it is completely molded for the reception of the heel.

While the mechanism for splitting, tongue-cutting and flap-molding have many features of novelty considered as unitary mechanisms, their cooperative organization in a single machine is believed to be broadly new and constitutes one important aspect of the invention. It is, moreover, believed that splitting mechanism and flap-molding mechanism have not been heretofore associated in 20 cooperative relation and this combination constitutes another broad aspect of the invention.

The invention includes also within its scope the novel method of preparing soles for wood heels herein shown as carried out by the machine disclosed, but obviously the 35 method is capable of being practiced by other or different instrumentalities.

The invention will be best understood and appreciated from the following description of one form of machine embodying it, which 40 has been selected for purposes of illustration and which, together with the method of using it, is shown in the accompanying drawings, in which—

Fig. 1 is a view in side elevation, partly 45 in section, of the machine;

Fig. 2 is a plan view of the sole carrier and associated parts;

Fig. 3 is a view in front elevation of the 50 sole-pressing member and associated parts;

Fig. 4 is a view in front elevation, partly 55 in section, of the sole carrier;

Fig. 5 is a detail view of the mechanism 60 for operating the sole-pressing member;

Figs. 6, 7 and 8 are sectional views, on an 65 enlarged scale, showing successive steps in the cycle of the machine; and

Fig. 9 is a view in perspective of the rear 70 end of a sole which has been operated upon by the machine.

The machine in general comprises a frame 75 10 in which is mounted a cam shaft 12 carrying the various cams of the machine and driven through a one-revolution clutch, not shown, of any commercial construction. The 80 forward portion of the machine frame is pro-

vided with horizontal dove-tailed ways 14, in which is mounted the carrier slide 16 having secured to its upper face a carrier plate 18 upon which the sole is positioned preliminarily to its presentation to the machine. 70 The plate 18 is roughened or corrugated upon its surface to retain the sole more securely and adapted to be reciprocated with the slide 16 forwardly and rearwardly. The slide 16 is actuated automatically by a cam lever 17 pivotally mounted in the frame 10 at its lower end upon a stud 19 and connected at its upper end through a link 15 to a pin 13 carried between ears projecting from the lower side of the slide 16. The cam lever 17 is provided with a cam roll 21 through which 75 rocking movement is imparted to the lever by a cam of suitable contour on the cam shaft. The cam is so shaped that on starting the machine the carrier is moved inwardly, presenting the sole first to the splitting knife and then dwelling in its inmost position, as will hereinafter appear, for the purpose of permitting the flap-molding and tongue-cutting operations to take place.

In order to grip the sole upon the carrier plate 18, a pair of clamping devices 59 are mounted upon the carrier slide 16 and arranged to move into clamping engagement with the sole at a predetermined point in the inward travel of the carrier. The clamping devices each comprises an arm pivotally connected to the outer end of a transverse clamp slide 51 and having also an intermediate link 61 connecting it to the plate 18. A compression spring 53 is interposed between the inner ends of the clamp slides 51 and this acts continually to urge the clamp slides outwardly and, consequently, to swing the clamping devices upwardly into releasing position. Each clamp slide is provided at its outer end with a roll 55 which runs upon the face of a cam plate 57, thus limiting the outward movement of the slide at all times and having an inclined face which acts when the carrier slide is moved and at the proper time in its travel to force the clamp slide positively inwardly whereupon, on account of the link connection 61, the clamp arm 59 is swung forcibly into engagement with the sole. 110 Each clamp arm 59 is provided at its inner end with an enlarged head, in which is mounted a clamping foot 63, backed up by a spring of sufficient tension to allow for soles of varying thickness and at the same time to exert sufficient clamping action upon the sole to hold it reliably against displacement in the position in which it has been located in the carrier.

The splitting knife together with the means for supporting and moving it will now be described. The knife 71 is secured to the lower side of a knife carrier 73 mounted to slide forwardly and rearwardly in guideways formed in a bracket 75, which is carried 115 120 125 130

by the machine frame and mounted therein upon a transverse shaft 111. The knife carrier 73 and the splitting knife is supported against the thrust of the sole and held stationary during the splitting operation and is thereafter retracted in order to permit the tongue-cutting operation to take place, as will presently appear. A pair of toggle links 77 are interposed between the rear end of the knife slide 73 and a stationary stud 79 in the machine frame and are connected at their joint through a link 81 with a rocking lever 83 pivoted at its forward end to the machine frame by a transverse shaft 85. The rocking lever 83 carries an intermediate cam roll 84 which is rocked by a cam on the cam shaft 2 at the proper time in the cycle of the machine, so as to break the toggle links and retract the splitting knife. It will be observed that the straightened toggle links constitute a rigid support for the splitting knife at all other times.

In order to control the presentation of the sole to the splitting knife and to regulate the thickness of a flap 40 being split, which flap will be referred to as a heel-seat flap, a sole-pressing roll 91 is provided at a point above the carrier slide and adjacent to the edge of the splitting knife. This is carried by the bracket 75 already mentioned as being pivotally supported upon the shaft 111 and which, at its forward end, is provided with a head 76, see Fig. 3. The head 76 at each side is provided with vertical guide-ways in which are mounted slides 93, each formed at its lower end to constitute a bearing for a trunnion 95 of the presser roll 91 and having an inclined face at its upper end. Each slide 93 is normally pressed upwardly by a spring, not shown, and is limited in its vertical movement by engagement with a wedge-shaped face, one of which is formed at each end of a cross bar 97. The bar 97 is also mounted in the head 76 and guided for transverse movement, which is effective in one direction to force the slides 93 downwardly and in the other to permit them to rise equally in their vertical guide-ways. The vertical position of the sole-pressing roll 91 may thereafter be adjusted by moving the bar 97 transversely. In order to provide for quick adjustment of this bar, it is provided with an upstanding lug 101 into which is threaded a spindle 103 freely rotatable in a lug 105 carried by the bracket 75 and having a hand wheel 107 at its outer end.

Upward movement of the bar 97 and, consequently, of the bracket 75 and the presser roll 91 carried thereby is limited and opposed by a spring-pressed plunger 113 which is mounted in a chamber in the front part of the machine frame and pressed downwardly by a compression spring 115, the effective strength of which can be adjusted by a screw 117. This arrangement permits a limited

yielding movement of the presser roll away from the carrier slide to compensate for variations in thickness of the soles being operated upon and as the bracket 75 carries the splitting knife with it, it will be apparent that the thickness of the flap is maintained uniform and that any variations which occur are thrown into the thickness of the body of the heel-seat remaining beneath it.

It is desirable that the presser roll 91 should be lifted so as not to engage the sole when the latter is being withdrawn after the various operations have been completed. Accordingly, the bracket 75 is formed with a rearwardly extending arm 119 which is connected at its rear end through a link 121 to one arm 123 of a lever pivoted to the machine frame upon a stud 125, and carrying on its other arm a cam roll 127 which is operated by a cam on the cam shaft 12 at the proper time in the cycle of the machine to swing the bracket 75 upwardly at its forward end and leave the presser roll 91 clear of the work.

It is frequently desired to vary the thickness of the flap at different points in the length, as by increasing its thickness toward the edge which is connected to the sole. In order to provide automatically for varying the thickness of the flap longitudinally, the axis of the presser roll 91 is disposed eccentrically with respect to the axis of its trunnions 95. The right-hand trunnion has fixed to it a downwardly extending arm 131 carrying at its lower end a cam roll 133 which runs in a cam slot 135 formed in a cam plate 137 adjustably secured by a wing nut 139 passing through a slot in the plate in adjusted position upon the carrier slide 16. In the construction herein shown, the slot 135 acts to hold the arm 131 in stationary position during the first part of the inward movement of the carrier slide, as the slot is horizontal and parallel to the path of the slide. At its forward end, the slot 135 turns downwardly and its front wall 141 acts upon the roll 133 when the carrier slide has been moved inwardly to that point to cause the arm 131 to swing in a counter-clockwise direction, turning the trunnions 95 and rocking the presser bar 91 bodily away from the sole. Consequently, the bracket 75 and the splitting knife carried thereby will be displaced downwardly with respect to the carrier slide and the sole so that the thickness of the flap will be correspondingly increased. It will be observed that the thickness of a flap longitudinally can be controlled as desired by suitably shaping the cam slot 135 and that the point at which the thickening commences to take place can be controlled by altering the position of the cam plate 137 longitudinally on the carrier slide. By adjusting the angular position of the cam plate 137 about the axis of the wing nut 139, a flap of pro-

gressively increasing thickness may be formed.

Should it be desired to vary the thickness of the flap transversely, the presser roll 91 may be correspondingly shaped. Under these circumstances, the resiliency of the sole may be relied upon to cause its transverse surface to conform to the longitudinal shape of the roll or, where that resiliency is regarded as insufficient, the effect may be intensified by suitably shaping the transverse surface of the carrier plate 18. If it is desired to thicken the flap at a central zone, the contour of the face supporting the sole may be correspondingly shaped.

In order to obtain uniform splitting, it is desirable that the cutting edge of the splitting knife 71 should be located as closely as possible to the line of maximum pressure between the presser roll 91 and the carrier slide. To this end, the rear face of the roll 91 is backed off, as indicated in Fig. 1. Consequently, the splitting knife may be advanced close to said line of maximum pressure without danger of the flap binding between the upper surface of the knife and the roll.

In order that the tongue-cutting operation may be carried out with the sole in place upon the carrier slide, the rear end of the plate 18 is provided with a die opening 23 having a contour of the shape which it is desired to impart to the heel-seat tongue. To support the sole during the splitting operation, this aperture is closed by a movable filling plate or shutter 25, normally flush with the surface of the plate 18, so that the plate and shutter constitute an uninterrupted support for the sole. At the proper time in the cycle of the machine, the shutter is displaced to make the die opening 23 effective, so that a portion of the material of the heel-seat may be depressed into it as will presently appear.

The shutter 25 is mounted upon the end of a lever 27 pivotally supported upon the pin 13 of the carrier slide and having a short depending arm 29 at right angles thereto. Pivotally connected to the lower end of the arm 29 is a forwardly-extending spring-pressed stop 31, so located as to contact with a stop pin 33 fixed in the frame of the machine. The arrangement is such that on the movement of the carrier slide into its outward position, the stop 31 engages the stop pin 33 and swings the lever 27 upwardly, carrying the shutter into the position shown in Fig. 1. The shutter is provided with a central raised portion and with a transversely-extending rib 35 which contacts with the under surface of the carrier plate 18 and so limits the upward movement of the shutter, the spring stop 31 supplying a slight amount of lost motion to insure accurate seating of the shutter.

The shutter 25 is held positively in its uppermost position when the table moves inwardly and is permitted to drop at the end of its rearward movement by mechanism which will now be described. The carrier slide 16 carries at each side a transversely movable plunger 37 pressed inwardly by a leaf spring 39 and shaped at its inner end to underlie the rib 35 of the shutter and so latch it in place. The under side of the end of each plunger 37 is beveled to permit the rib 35 to pass by when the shutter is raised. The outer end of each plunger is provided with a downwardly projecting lip 41 which contacts with a cam projection 43 (Fig. 2) located at the inner end of the guide-way and moves each plunger outwardly when the carrier slide reaches the limit of its initial movement, so that the shutter is free to fall by its own weight from the die opening 23.

The tongue-cutting knife 151 is secured to a knife carriage 153 mounted for reciprocation in horizontal guide-ways 154 formed in the frame of the machine. The knife carriage 153 is connected by a link 155 to the upper end of a rocker lever 157 pivotally mounted upon a stud 159 in the frame of the machine. The rocker lever 157 has a forwardly projecting arm which carries a cam roll 161 acted upon by a cam on the cam shaft 12 at the proper time in the cycle of the machine to rock the lever 157 and advance or retract the knife slide 153. The cutting edge of the tongue-cutting knife 151 is at such a height that it moves practically in contact with the under surface of the carrier plate 18 when the carrier slide is in its inmost position and, consequently, the material forced through the die opening 23 is within its range of action.

The means for forcing or bulging the material of the heel-seat through the die opening for die-shaping this portion of the heel-seat will now be described in connection with the mechanism for molding the flap split from the heel-seat. The machine frame is formed with vertical bearings for a plunger 171 located in line with and above the point reached by the heel-seat of the sole at the conclusion of the splitting operation. The plunger 171 carries at its lower end a die member or bulger, shaped in a manner well-known in the art, for forcing or bulging the material of the heel-seat into the die opening. The rear face of the plunger is provided with rack teeth 173 which mesh with the teeth of a gear segment 175 formed in the face of a rocker lever 179 pivotally mounted upon a transverse shaft 177 in the machine frame. The segment is connected at its rear end by a link 181 to one arm of the bell crank lever 183, pivotally mounted in the machine frame upon the stud 185, and carrying in its other arm a cam roller 187 which is acted upon by a cam on the cam shaft 12 at the proper

time in the cycle of the machine to impart vertical movement to the plunger 171. The link 181 is of a two-part construction, the arrangement being such that the plunger 171 is yieldingly depressed and positively raised.

The lower end of the plunger 171 carries not only the plate for bulging the heel-seat into the die opening 23 but also the flap-molding mechanism and a single depression of the plunger 171 effects both the bulging and the flap-molding operations. Fixed to the lower end of the plunger 171 is a head 191, the lower face of which is shaped to constitute the upper molding member of a pair and corresponds to the shape required ultimately in the breast flap. Pivotaly mounted upon a lug 193 projecting rearwardly from the plunger head 191 is the lower molding member 195, the upper surface of which is shaped to correspond to the surface of the upper molding member. The lower molding member 195 is normally swung downwardly about its pivot by a spring, not shown, against the front end of the knife carrier 73 so that the molding members normally stand open and ready to receive the breast flap as the latter leaves the edge of the splitting knife 71. Preferably, the contour of the molding members will be shaped to over-mold the flap, that is, to give it a greater deformation in contour than it is ultimately required to retain.

The bulger is constituted by a plate 201 fixed to the lower surface of the hinged lower molding member 195, the dimensions and shapes of the various parts being such that when the breast flap is engaged between the molding members 191 and 195 the lower surface of the bulger plate 201 will be substantially horizontal and enter the die opening 23 more or less in bulging the material of the heel-seat into and through the opening.

The operation of the machine will now be described with particular reference to Figs. 6 to 8. The carrier slide being in the position indicated in Fig. 1, a sole is placed thereon, grain side up, with its heel end toward the presser roll 91. The sole may be located freely and accurately by reference to suitable gauges. The machine is then started and the inward movement of the carrier slide causes the sole clamps 63 to descend and clamp the sole firmly to the upper surface of the carrier plate. Continued inward movement of the carrier slide advances the heel-seat end of the sole beneath the sole-pressing roll 91 and against the forward edge of the splitting knife 71, so that a breast flap is split from the heel-seat of the sole, and this rides up immediately from the edge of the splitting knife between the upper and lower molding members 191 and 195. If desired, the presser roll 91 is rocked in the manner described during the feeding movement to vary the thickness of the flap. Fig. 6 represents the parts of

the machine in the position occupied at the conclusion of the flap-splitting operation except that the shutter 25 has not dropped out of the die opening or cavity.

When the carrier slide reaches the inward limit of its travel, the shutter 25 is tripped and falls automatically, as shown in Fig. 7, and at this time the die opening 23 is located in line with and beneath the plunger 171. The feed cam at this point reaches a dwell, so that the carrier slide is maintained in its inmost position while the ensuing operations take place. The splitting knife 71, which has heretofore been sustained against the thrust of the sole, is retracted and removed from the sole by the breaking of the toggle links 77. Figs. 7 and 8 show the splitting knife as retracted to its inoperative position with its forward edge clear of the downwardly moving parts carried by the plunger 171. During the dwell of the carrier slide, the plunger 171 is depressed, first to cause the molding member 195 to be rocked upwardly about its pivot to engage the breast flap against the upper molding member 191 and to bring about the molding operation, and in the second place to cause the bulger plate 201 to depress the unsupported portion of the heel-seat material remaining beneath the flap through the die opening 23, thus die-shaping the material preparatory to the tongue-cutting operation. The tongue-cutting knife 151 is then moved forward into the portion of the heel-seat which is bulged through the aperture to form the outline of the narrow bevel-edged tongue required. Fig. 7 shows the plunger depressed for the molding and bulging operations and Fig. 8 shows the tongue-cutting knife advanced to its final position in the tongue-cutting operation.

Thereafter, the tongue-cutting knife 151 is retracted, the plunger 171 is raised to release the molded breast flap, and the presser roll 91 with the splitting knife 71 is raised by the rocking of the bracket 75 to release the sole and to clear the molded breast flap so that the benefit of the molding is not lost by drawing the molded flap forwardly beneath the presser roll. The carrier slide is then moved forwardly, the sole clamps 63 are raised to release the sole and the shutter 25 is raised and locked in raised position, ejecting any portion of the sole which tends to hang in the die opening. The splitting knife is finally moved forward and the bracket 75 rocked to its initial position in readiness for a repetition of the cycle.

Fig. 9 represents the heel-seat end of a sole as it comes from the machine, the flap 40 having been separated from the heel-seat and molded as explained, and the bevel-edged tongue 42 having been formed in the heel-seat within the horse-shoe shaped trimming 44. All that remains to be done preparatory to receiving the wood heel is to remove the

trimming 44 and this may be done by hand or by such a machine as that disclosed in the pending application for U. S. Letters Patent Serial No. 257,421.

5 It will be apparent that in designing the machine hereinabove described, it was necessary first to evolve a method of preparing soles different from that heretofore practiced and involving a different sequence of steps. 10 The illustrated machine comprises one combination of suitable instrumentalities for practicing this novel method but the method may be carried out by other and different instrumentalities. In this connection, particular attention is called to the steps of splitting the flap from the heel-seat end of a sole and inserting the flap as formed between molding members. This procedure, with its obvious advantages, is believed to be broadly 20 new regardless of means for carrying it out. The same is true with respect to performing simultaneously the operations of molding the flap and die-shaping the body of the heel-seat in which the tongue is to be cut.

25 Having thus described our invention, what we claim as new and desire to secure by Letters Patent is:

1. A machine for operating on soles, having in combination, a knife constructed and 30 arranged to split a flap from a sole, a knife arranged to cut a tongue from the portion of the sole from which the flap has been split, and means for relatively moving a sole and said splitting knife and relatively moving 35 the sole and said tongue-cutting knife to effect splitting and tongue-cutting operations.

2. A machine for operating on soles, having in combination, a splitting knife, means 40 to present a sole thereto for forming a heel-seat flap therein, and a tongue-cutting knife operative thereafter to form a tongue in the remaining portion of the heel-seat.

3. A machine for operating on soles, having in combination, a splitting knife, means 45 to present a sole thereto for forming a heel-seat flap therein and for holding the sole in the position it occupies at the conclusion of the splitting operation, and a tongue-cutting knife movable to form a tongue in the sole while so held.

4. A machine for operating on soles, having in combination, a splitting knife, a carrier for presenting a sole thereto for splitting 55 a flap therein, means for bending the flap away from the heel-seat, and a tongue-cutting knife movable to form a tongue in the portion of the heel-seat beneath the flap.

5. A machine for operating on soles, having in combination, a splitting knife, a carrier movable to present a sole to the knife for splitting a flap therein, the knife being then removed from the sole, and a tongue-cutting knife movable to form a tongue in the sole 65 while it remains in the position it occupies

at the conclusion of the splitting operation.

6. A machine for operating on soles, having in combination, means for clamping and feeding a sole, a splitting knife supported against the thrust of the sole during the flap 70 splitting operation and being constructed and arranged to be retracted thereafter, and a tongue-cutting knife movable upon the retraction of the splitting knife to form a tongue in the portion of the sole from which 75 the flap has been split.

7. A machine for operating on soles, having in combination, means for clamping and feeding a sole with its heel-seat end in advance, a splitting knife, a train of mechanism 80 for supporting said splitting knife against the thrust of the sole during the flap splitting operation and to retract the knife thereafter, and a tongue-cutting knife movable after the retraction of the splitting knife to form 85 a tongue in the heel-seat of the sole.

8. A machine for operating on soles, having in combination, a splitting knife, means for presenting a sole thereto to form a flap therein, means for die-shaping the portion 90 of the sole from which the flap is cut, and a tongue-cutting knife acting to cut a tongue therein.

9. A machine for operating on soles, having in combination, a splitting knife, means 95 for presenting a sole thereto to form a flap therein and to separate the flap from the body of the heel-seat, means for die-shaping the body of the heel-seat, and a tongue-cutting knife acting to cut a tongue therein. 100

10. A machine for operating on soles, having in combination, a splitting knife, means for presenting a sole thereto to split a flap from the heel-seat thereof, means for positively holding the flap thus formed away 105 from the heel-seat, and means for cutting a tongue in the body of the heel-seat while the flap is so held.

11. A machine for operating on soles, having in combination, a splitting knife, a sole carrier movable to present a sole thereto for a splitting operation and having a die opening therein, means for forcing the unsplit portion of the sole into the die opening at the conclusion of the splitting operation, and a tongue-cutting knife arranged to act on the sole adjacent to said die opening. 110

12. A machine for operating on soles, having in combination, a splitting knife, a sole carrier movable to present a sole thereto to effect a splitting operation and having a die opening therein, means for filling the die opening during the splitting operation arranged to be displaced at the conclusion of the splitting operation to permit the sole to be forced into the opening, and a tongue-cutting knife movable adjacent to said opening. 115

13. A machine for operating on soles, having in combination, a splitting knife, a sole carrier having a U-shaped opening and a fill- 120

ing plate therefor, means for moving said carrier to present a sole to the splitting knife while the filling plate is in position, the filling plate being displaced thereafter, a plunger for forcing a portion of the sole into said 5 U-shaped opening, and a knife for operating upon the portion of the sole shaped by said opening.

14. A machine for operating on soles, having in combination, a splitting knife, a sole carrier having a die opening therein and a filler plate normally latched in position to close said opening, means for moving said carrier to present a sole to the splitting knife, 10 means for tripping said filler plate when the carriage reaches a predetermined point in its travel, a presser member movable thereafter to displace a portion of the sole into said die opening, and a knife for operating upon the 15 portion so displaced.

15. A machine for operating on soles, having in combination, a splitting knife, a sole carrier guided for movement to present a sole thereto, oppositely disposed sole clamping devices mounted upon the carrier and being spaced from the carrier when the latter is in its initial position, and means for moving said clamping devices into engagement with the sole when the carrier reaches a predetermined point in its travel.

16. A machine for operating on soles, having in combination, a sole carrier and splitting knife relatively movable to split a flap from a portion of a sole, and means acting automatically in timed relation thereto for molding the flap so split.

17. A machine for operating on soles, having in combination, a sole carrier and splitting knife relatively movable to split a flap from a portion of a sole, and cooperating molds constructed and arranged to receive the flap as it is formed and to close thereon with molding pressure at the conclusion of the splitting operation.

18. A machine for operating on soles, having in combination, a sole carrier and splitting knife relatively movable to split a flap from the heel-seat of a sole, a mold so located as to deflect the flap as split from the body of the heel-seat, and a cooperating mold movable into molding position at the conclusion of the splitting operation.

19. A machine for operating on soles, having in combination, a movable plunger, hinged mold members carried by the plunger and initially separated, means for presenting between said mold members a heel-seat flap, an abutment in line with the path of movement of said plunger, and means for automatically moving the plunger to close the mold members against the abutment and upon the inserted flap.

20. A machine for operating on soles, having in combination, a presser member having cooperating flap molding members mounted

thereon, one of said members being a relatively thin plate adapted to be inserted between the body of the heel-seat of a sole and a flap split therefrom but connected thereto at its breast edge, an abutment for supporting said molding plate, and means for moving the presser member toward the abutment to force the molding members toward each other for molding the flap without disturbing its attached edge.

21. A machine for operating on soles, having in combination, a splitting knife, a sole carrier having a die opening therein and a hinged plate filling said opening in the initial position of the carrier, means for releasing said plate for removal from the opening at a predetermined point in the travel of the carrier, and means for restoring said plate to position when the carrier is moved to initial position.

22. A machine for operating on soles, having in combination, a splitting knife, a sole carrier guided to present a sole to said knife, and a train of mechanism constructed and arranged to support said knife against the thrust of the sole during the splitting operation and then to retract said knife to an inoperative position to permit other operations to be effected upon the sole.

23. A machine for operating on soles, having in combination, sole feeding means, a splitting knife, toggle links connected to the splitting knife and arranged in straightened condition to hold said knife rigidly against the thrust of a sole, and means for breaking said toggle links at the conclusion of the splitting operation to retract the splitting knife from the sole.

24. A machine for operating on soles, having in combination, a pair of molding members relatively movable to engage and mold a heel-seat flap attached at its breast edge to a sole, together with means for die-shaping and cutting a tongue in the heel-seat beneath the flap during the molding operation.

25. A machine for operating on soles, having in combination, a plate having a die cavity, a pair of molding members movable first to engage a flap attached at one edge to a sole and then to force the portion of the sole beneath the flap into said die cavity, and means for cutting the portion of the sole thus displaced.

26. A machine for operating on soles, having in combination, sole feeding mechanism, a flap splitting knife, flap-molding mechanism, and a tongue-cutting knife, all organized and arranged to perform in timed relation the operations of flap-splitting, flap-molding and tongue-cutting upon a sole presented by said feeding mechanism.

27. A machine for operating on soles, having in combination, a sole carrier, a knife for splitting a flap from the heel-seat of a sole presented thereto by said carrier, means

for engaging and molding the flap thus formed, and means for cutting a tongue in the heel-seat beneath the flap during the molding operation.

28. A machine for operating on soles, having in combination, a sole feeding slide having a die opening, a splitting knife for forming a flap in one end of a sole presented by the feeding means, cooperating mold members for molding the flap and acting also to displace a portion of the sole into the die opening, and a tongue-cutting knife arranged to act upon the portion of the sole thus displaced.

29. A machine for operating on soles, having in combination, a splitting knife, a sole carrier for presenting a sole thereto, a member for pressing the sole upon its carrier at a point adjacent to the knife, a yielding support for the pressing member, and a wedge device movable relatively to said member and constructed and arranged uniformly to vary the pressure of the pressing member upon said sole throughout its effective pressing surfaces.

30. A machine for operating on soles, having in combination, a splitting knife, a sole carrier movable for presenting a sole thereto, a bracket mounted for movement toward and from said carrier and having a sole pressing member therein, means for yieldingly supporting said pressing member in the bracket, and means for moving the bracket to separate the pressing member from the sole carrier at a predetermined time after the latter has completed its sole presenting movement.

31. A machine for operating on soles, having in combination, a sole carrier guided for feeding movement in a fixed path, a bracket mounted for movement toward and from the path of the carrier, a splitting knife and a sole pressing member both mounted in said bracket and bodily movable therewith, and means for controlling the position of said bracket.

32. A machine for operating on soles, having in combination, a sole carrier guided for feeding movement in a fixed path, a sole pressing member disposed above the path of the carrier and movable toward and from the same, a splitting knife having a stationary cutting edge located adjacent to the pressing member, and means for lifting the pressing member at a predetermined point in the travel of the carrier.

33. A machine for operating on soles, having in combination, a splitting knife, a sole carrier movable to present a sole thereto, a sole pressing bar eccentrically mounted above the path of said carrier adjacent to the splitting knife and connected to said knife to control its position, and a cam adjustably mounted on said carrier and having connections for turning said presser bar at a predetermined point in the travel of the carrier

to permit bodily movement of the knife transversely to the plane of the sole.

34. A machine for operating on soles, having in combination, cooperating flap molding members, a sole feeding device for presenting a sole having a flap split therein so that the flap alone is inserted between the molding members, and means acting in timed relation to the feeding device to actuate the molding members.

35. A machine for operating upon soles of shoes having, in combination, means for positioning in a machine a sole a portion of which has been split to form a heel-seat flap, means for positioning the flap in the machine, and means constructed and arranged to operate upon the rear portion of the sole and upon the flap thus positioned to tongue the heel-seat portion of the sole and to mold the flap to fit the breast portion of a heel respectively.

36. A machine for operating upon soles of shoes having, in combination, means for positioning in a machine a sole a portion of which has been split to form a heel-seat flap, means for positioning the flap in the machine, and means constructed and arranged to operate simultaneously upon the rear portion of the sole and upon the flap thus positioned to tongue the heel-seat portion of the sole and to mold the flap to fit the breast portion of a heel respectively.

37. A machine for operating upon soles having, in combination, a splitting knife, a power operated sole carrier movable for presenting a sole to the knife, a bracket mounted for movement toward and from the carrier and having a sole pressing member therein, means for yieldingly supporting the pressing member against the sole, and power operated means arranged in timed relation to the sole carrier for moving the bracket to separate the pressing member from the sole carrier after the latter has completed its sole pressing movement.

38. A machine for operating on soles, having in combination, a splitting knife, a sole carrier movable for presenting a sole thereto, a bracket mounted for movement toward and from said carrier and having a sole pressing member therein, means for yieldingly supporting said pressing member in the bracket, and cam operated means for moving the bracket to separate the pressing member from the sole carrier at a predetermined time after the latter has completed its sole presenting movement.

39. A machine for operating on soles, having in combination, a sole carrier guided for feeding movement in a fixed path, a sole pressing member disposed above the path of the carrier and movable toward and from the same, a splitting knife constructed and arranged to be moved bodily into and out of operation relatively to the sole carrier, and means for lifting the pressing member at a

predetermined point in the travel of the carrier.

40. The method of preparing a sole for the reception of a wood heel which consists in splitting a flap from the heel-seat end of the sole, separating the flap as it is split from the heel-seat end of the sole, bulging the body of the heel-seat end of the sole, and molding the flap and simultaneously cutting a tongue in the heel-seat end of the sole while it is bulged.

41. The method of preparing a sole for the reception of a wood heel which consists in splitting a flap from the body of the heel-seat end of the sole, and molding the flap to conform to the breast of the heel and simultaneously cutting a tongue from the body of the heel-seat portion of the sole.

42. The method of preparing a sole for a wood heel which consists in splitting a flap from the heel-seat end thereof, inserting the flap as it is being split between molding members, and then molding the flap while its forward edge is unsevered from the remainder of the sole.

43. The method of preparing a sole for a wood heel which consists in forming a heel-seat flap therein which is attached at one edge to the sole, simultaneously molding the flap and die-shaping the body of the heel-seat, and cutting a tongue in the latter while so shaped.

44. The method of preparing a sole for a wood heel which consists in forming a heel-seat flap therein which is attached at one edge to the sole, inserting a molding member between the flap and the body of the heel-seat, molding the flap upon said member, and simultaneously cutting a tongue in the body of the heel-seat.

In testimony whereof we have signed our names to this specification.

ARTHUR BATES.
FRANK BYCROFT KEALL.
